Primary Examiner — Robin V Webster(74) Attorney, Agent, or Firm — Tim Tingkang Xia, Esq.; Locke Lord LLP(57) CLAIM

The ornamental design for a shower head kit, as shown and described.

DESCRIPTION

FIG. 1 is a front elevation view of a shower head kit according to my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

The broken lines showing of a shower head kit are for the purpose of illustrating environmental structures of the shower head kit and form no part of the claimed design.
